(57) **CLAIM**

The ornamental design for an arthritis glove as shown and described.

DESCRIPTION

FIG. 1 is a perspective view of an arthritis glove showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The short thick evenly spaced broken lines in the drawings depict stitching and form no part of the claimed design. The short thin evenly spaced broken lines in the drawings depict portions of arthritis glove and form no part of the claimed design.

1 Claim, 8 Drawing Sheets
